UNITED STATES PATENT OFFICE.

DAVID FRANK, OF BROOKLYN, NEW YORK, ASSIGNOR OF ONE-HALF TO
JOHN TROUNSTINE, OF NEW YORK, N. Y.

DESIGN FOR AN END FRAME FOR METAL BEDSTEADS.

SPECIFICATION forming part of Design No. 26,688, dated February 23, 1897.

Application filed January 16, 1897. Serial No. 619,490. Term of patent 7 years.

To all whom it may concern:

Be it known that I, DAVID FRANK, a citizen of the United States, residing at the city of Brooklyn, in the county of Kings and State of New York, have invented and produced a new and original Design for the End Frame of a Metal Bedstead, of which the following is a specification, reference being had to the accompanying drawing, forming part thereof, and which illustrates in front elevation the end frame of a metal bedstead embodying my design.

The leading feature of my design consists in the ornamental outlines described by the metal rods which compose the main body of the frame intermediate the outer vertical posts and above the lower connecting-rail, substantially as shown in the accompanying drawing.

In the drawing, A designates the outer vertical posts. B denotes the usual lower con-

necting-rail, and D D indicate the upper and lower horizontal rails, above the upper one of which are the corresponding metal-rod ornamental configurations E E, while between said rails D D are the vertical rods F F and G G, between the latter of which are the ornamental metal-rod configurations H, the latter occupying a rectangular outline or panel and extending from the corners to the center thereof, whereat is a box or casting I, substantially as shown in the drawing.

What I claim is—

The design for the end frame of a metal bedstead; substantially as shown and described. 35

Signed at New York, in the county and State of New York, this 8th day of January, 1897.

DAVID FRANK.
